United States Patent Office

Des. 193,117
Patented June 26, 1962

193,117

BOTTLE

Martin Umanoff, Huntington, N.Y., assignor to R. A. MacPlum Industries, Inc., Clifton, N.J., a corporation of New Jersey

Filed Mar. 15, 1961, Ser. No. 64,308

Term of patent 14 years

(Cl. D58—8)

Fig. 1

Fig. 2

Fig. 3

I claim:

The ornamental design for a bottle, as shown.
